GEORGE H. BAILEY, OF JERSEY CITY, NEW JERSEY, ASSIGNOR TO THE AMERICAN WATER AND GAS-PIPE COMPANY.

Letters Patent No. 65,863, dated June 18, 1867.

IMPROVED DEVICE FOR TAPPING CEMENT-LINED PIPES.

The Schedule referred to in these Letters Patent and making part of the same.

TO ALL WHOM IT MAY CONCERN:

Be it known that I, GEORGE H. BAILEY, of Jersey City, in the county of Hudson, and State of New Jersey, have invented a new and improved Mode of Tapping Pipes of Wrought Iron and Cement; and I do hereby declare that the following is a full, clear, and exact description thereof, reference being had to the accompanying drawings, making a part of this specification, in which—

Figure 1 is a cross-section of a wrought-iron pipe having cement applied to it, with my improved tap inserted.

Figure 2 is a longitudinal section of the pipe and tap.

Figures 3, 4, and 5, show the parts of the tap in detail.

Similar letters of reference indicate corresponding parts in the several figures.

The mode hitherto adopted of tapping pipes of iron and cement, is to attach the stop-cock to the outside of the iron pipe by means of solder, and when thus secured to bore through the pipe and the cement on the inside thereof. By this mode of tapping the connection requires to be made with great care, and by a person skilled in soldering. Even in the hands of a careful person there is danger of sealing or chipping off the cement lining in boring, leaving a portion of the iron exposed to oxidation, and liable to rapid decay.

To remedy the objection to the above-mentioned mode of tapping the combined iron and cement pipes, my invention consists in the employment of a flanged tube having a screw-thread upon it, which tube is open at both ends and applied to the iron pipe by means of a lock or clamp-nut, which will form a substantial connection, as will be hereinafter described.

To enable others skilled in the art to understand my invention, I will describe its construction and operation.

In the accompanying drawings, A represents the metal shell or pipe; B the cement lining; C the outside covering of cement; D the flanged nipple, and E the locking-nut.

The mode of application is as follows: The iron, in the process of forming it into pipes, is punched with a hole of proper size. A metal tube or nipple having a screw-thread cut upon it, and a flange, *a*, formed on it near one end, is passed through the hole which is through the pipe, so as to leave the flange *a* on the inside of this pipe. The lock-nut is then screwed upon the tube or nipple from the outside of the pipe, so as to draw and clamp the metal of the pipe between the flange *a* and nut *E*, as shown in the drawings. The nipple is of such length that when screwed fast sufficient room will remain above the nut to attach the stop-cock. In the process of lining the pipe the outer end of the nipple is closed with a cap or plug, *G*; the flanged end becomes entirely bedded in the cement, and the nipple, as far as the external plug or cap, is filled at the same time. The end of the nipple projects into the pipe beyond the flange just far enough to be entirely covered with cement, without giving any considerable thickness beyond it. By this means I furnish a pipe already tapped, and nothing remains to be done, when it is desired to connect at any given point, but to attach the stop-cock by screwing it on the projecting end of the nipple and boring through the cement to the inside of the pipe. This may be done without disturbing the cement lining. The mode of tapping with a nipple which is open at both its ends, as above described, renders it unnecessary to drill through the iron pipe in the act of making a connection, and by extending the inner end of the nipple nearly to the inner surface of the lining, the latter is free from injury during the clearing of the cement from the interior of this nipple.

Having described my invention, what I claim as new, and desire to secure by Letters Patent, is—

1. The combination of the tap *D*, bored through from end to end, with the combination iron and cement pipe, substantially in the manner and for the purpose described.
2. Constructing the flange *a* upon the tube or nipple at an intermediate point between the ends thereof, as shown in fig. 4 of the drawings, so that when the device is applied to a cement-lined pipe, the cement lining shall not be liable to break off in tapping, substantially as described.

GEO. H. BAILEY.
